UNITED STATES PATENT OFFICE.

JOHN ANDERSON, OF LINCOLN, KANSAS.

METAL RAILWAY-TRACK CROSSING.

No. 918,113.

Specification of Letters Patent.

Patented April 13, 1909.

Application filed February 11, 1909. Serial No. 477,450.

To all whom it may concern:

Be it known that I, JOHN ANDERSON, a citizen of the United States, residing at Lincoln, in the county of Lincoln and State of Kansas, have invented certain new and useful Improvements in Metal Railway-Track Crossings, of which the following is a specification, reference being had to the accompanying drawings.

10 This invention relates to improvements in crossings at the intersections of railway tracks and highways or streets, and consists of the novel features of construction and the combination and arrangement of parts hereinafter described and claimed.

The object of the invention is to provide simple and practical steel or other metal planks to be arranged on opposite sides of the track rails to guide vehicle wheels there-
20 over, and also to provide improved fastening means for said metal planks or members.

The above and other objects of the invention are attained in its preferred embodiment illustrated in the accompanying drawings, in
25 which—

Figure 1 is a vertical cross section through a railroad track intersected by a highway or street, showing the application of the invention; Fig. 2 is a detail perspective of a portion of a track, showing the improved metal planks or members arranged on opposite sides of one of the rails of a track; and Fig. 3 is an inverted or bottom perspective of one of the metal members.

35 In the drawings 1 denotes ordinary track rails spiked or otherwise secured to the usual wooden cross ties 2, and the numerals 3 and 4 denote the two metal planks or members which are arranged longitudinally on opposite sides of each track rail at the point where the track is crossed by a highway, road, street, or the like. The members 3 are disposed upon the outer sides of the rails 1 and in contact with the outer faces of their
40 heads. Each of said members 3 is preferably constructed from a single metal sheet or plate of suitable thickness and it comprises a body of substantially inverted U-shape in cross section having an inclined top 5 and two
45 depending sides 6. The top 5 is inclined upwardly and inwardly so that its highest point is disposed substantially in the plane of the top of the rail 1 and the inner side wall 6 is disposed vertically and rests upon the outer base
50 flange of the track rail, the upper portion of

said side wall 6 being in contact with the head of the rail, as clearly shown in Fig. 1. The outer side wall 6 is preferably inclined downwardly and outwardly to a slight extent and its bottom terminates in an outwardly bent horizontal flange 8 adapted to rest upon the cross ties 2 and apertured at intervals, as shown at 9, so as to receive ordinary spikes 10 or equivalent fastenings. The inner member 4 is like the outer member 3 in all respects excepting one, and that is, the vertical wall 6^a is made longer so as to rest upon the top of the tie 2 in contact with the edge of the inner base flange of the rail 1 and so that the upper portion of said wall 6^a is spaced from the head of the rail, as shown at 6^b, to permit the flanges of car wheels to pass the member 4.

55 My improved means for effectively securing the two members in position consists in forming at their ends integral longitudinally extending arms 11 which are bent downwardly from their inclined top portions 5 to a point beneath the base flanges of the rails 1 and between two of the ties 2. Said lower ends of the arms 11 are bent angularly to horizontal positions, as shown at 12, and they are apertured, as at 13, to receive bolts 14. The latter also pass through the apertured ends of a cross piece or plate 15 arranged beneath the rail and upon the upper faces of the bent ends 12 of the arms 11, as clearly shown in Fig. 2 of the drawings. It will be noted that these cross pieces or plates 15, one of which is arranged at each end of each pair of the members 3, 4, will effectively hold them in position on opposite sides of the track rails and prevent lateral shifting movement. This construction also strengthens said members and prevents them from
60 being bent. The nuts 16 of the bolts 14 are preferably arranged on top of the cross plates 15 so that they will not work loose.

65 In using the invention, it will be understood that after the two members 3, 4 have been secured to the ties on the outer and inner sides of the track rails, the space between the members 4 and beyond the members 3 is filled up with gravel, crushed stone, asphalt, or other suitable material from
70 which the road, highway, street or the like is made, such material being indicated at 17 in Fig. 1. It will be seen that by constructing the members 3, 4, which, in effect, are metal planks, as set forth and arranging them and
75

securing them to the ties on opposite sides of each track rail at a highway or street, a very effective means is provided for guiding wheels of vehicles over the track rails. The construction of said members renders them strong, durable and comparatively inexpensive and the improved fastening means holds them effectively in position so that they cannot work loose.

10 Having thus described the invention what is claimed is:

1. In a track crossing, the combination with a road bed and track rails, of metal members arranged on the road bed on opposite sides of the track rails and each of substantially inverted U-form in cross section, the top of each member being inclined downwardly to a slight extent from the track rail and having its highest point disposed substantially in the plane of the head of the rail, the two members upon the inner sides of the rails being spaced from the latter and the two upon the outer sides of said rails being in contact with the head portions of the rails,

tongues formed integral with the top portions 25 of the members at their ends and bent downwardly beneath the base flanges of the track rails, the lower ends of said arms being bent angularly to a horizontal plane, cross plates arranged beneath the track rails and upon 30 said bent ends of the arms, and fastenings passed through said cross plates and the ends of the arms.

2. In a track crossing, the combination with the road bed and track rails, of metal 35 members arranged on opposite sides of the track rails, arms projecting longitudinally from the ends of said members and bent downwardly beneath the base flanges of the track rails and cross members extending 40 under the track rails and secured to the lower ends of said arms.

In testimony whereof I hereunto affix my signature in the presence of two witnesses.

JOHN ANDERSON.
